US0D1036855S

(12) **United States Design Patent** (10) **Patent No.:** **US D1,036,855 S**
(45) **Date of Patent:** **** Jul. 30, 2024**

(54) **INPUT DEVICE CARRYING CASE**

(71) Applicant: **Logitech Europe S.A.**, Lausanne (CH)

(72) Inventors: **Yueqi Yang**, Shanghai (CN); **Libao Wu**, Fremont, CA (US); **Tania Alvarez Moreno**, Miami, FL (US)

(73) Assignee: **Logitech Europe S.A.**, Lausanne (CH)

(***) Term: **15 Years**

(21) Appl. No.: **29/840,685**

(22) Filed: **May 31, 2022**

(51) LOC (14) Cl. **03-01**

(52) U.S. Cl.

(57) **CLAIM**

The ornamental design for an input device carrying case, as shown and described.

DESCRIPTION

FIG. 1 is a front perspective view of an input device carrying case showing our new design in a closed configuration;

FIG. 2 is a rear perspective view thereof;

FIG. 3 is a front plan view thereof;

FIG. 4 is a rear plan view thereof;

FIG. 5 is a top elevation view thereof;

FIG. 6 is a bottom elevation view thereof;

FIG. 7 is a left-side elevation view thereof;

FIG. 8 is a right-side elevation view thereof;

FIG. 9 is a front perspective view of the input device carrying case showing our new design in an opened configuration;

FIG. 10 is a rear perspective view thereof;

FIG. 11 is a front plan view thereof;

FIG. 12 is a rear plan view thereof;

FIG. 13 is a top elevation view thereof;

FIG. 14 is a bottom elevation view thereof;

FIG. 15 is a left-side elevation view thereof; and

FIG. 16 is a right-side elevation view thereof.

The broken lines shown in the figures show features the input device carrying case that form no part of the claimed design.
